UNITED STATES PATENT OFFICE

125,785

DESIGN FOR AN ADVERTISING SIGN

Charles E. Rohkar, Tulsa, Okla.

Application January 6, 1941, Serial No. 97,834

Term of patent 7 years

To all whom it may concern:

Be it known that I, Charles E. Rohkar, a citizen of the United States and resident of Tulsa, county of Tulsa, and State of Oklahoma, have invented a new, original, and ornamental Design for Advertising Signs, of which the following is a specification, reference being had to the accompanying drawing, forming a part thereof.

The figure is a perspective view of an advertising sign, showing my new design.

I claim:

The ornamental design for an advertising sign, substantially as shown.

CHARLES E. ROHKAR.
